UNITED STATES PATENT OFFICE.

SAMUEL W. HYATT, OF COLUMBUS, OHIO, ASSIGNOR TO HYATT IGNITION COMPANY.

SPARK-PLUG.

1,325,403.

Specification of Letters Patent. Patented Dec. 16, 1919.

Application filed July 30, 1918. Serial No. 247,430.

To all whom it may concern:

Be it known that I, SAMUEL W. HYATT, a citizen of the United States, residing at Columbus, in the county of Franklin and State of Ohio, have invented new and useful Improvements in Spark-Plugs, of which the following is a specification.

This invention has reference generally to improvements in that class of inventions known as internal combustion engines and more particularly relates to an improved spark plug.

It is the primary aim and object of the present invention to provide a device of the above mentioned character designed for producing a high frequency spark on the inside of the combustion chamber for insuring of the burning of the oil globules which contact with the insulator and electrodes thereby eliminating any possible chances of carbon formation on the sparking points which would cause a short circuit.

More particularly the present invention contemplates the provision of a device of the above mentioned character wherein the electrodes or poles are designed to provide two or more spark gaps, consequently producing an intensified spark at the sparking points and in addition these electrodes are of such construction that they are foul proof when in use.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts in the construction hereinafter described and the scope of the application of which is indicated in the appended claim.

The invention is clearly illustrated in the accompanying drawings, in which:—

Figure 1 is a vertical central section of the invention partly in elevation.

Fig. 2 is a bottom plan view thereof.

Fig. 3 is a vertical sectional detail of another form of the invention partly in elevation.

Fig. 4 is a bottom plan view thereof.

Similar characters of reference are employed in all of the above described views, to indicate corresponding parts.

Referring now, more particularly to the accompanying drawings there is provided a metallic casing indicated generally by the numeral 1 being preferably of a tubular configuration and having its lower portion reduced and exteriorly threaded as at 2 for facilitating the attachment of the spark plug in the customary manner. The reducing of the casing provides an interior annular shoulder 3 therein while mounted within the casing is an insulator body generally designated 4 formed with an enlargement 5 approximately medially of its ends and this enlargement in turn provides the shoulders 6 and 7, the lower 6 of which rests upon a copper gasket 8 which in turn engages the shoulder 3 while engaging against the upper surface of the upper shoulder 7 is another gasket 9 preferably of copper. Coöperating with the gaskets and removably yet rigidly holding the insulator body in a proper position within the casing is an exteriorly threaded bushing 10 which engages the interior threads near the upper portion of the casing and acts as a jam nut, as indicated. Carried within the insulator body is a pole or central electrode 11 the lower end of which projects slightly beneath the lower edge of the body and forms a spark terminal 12, while the upper end extends above the insulator body and is threaded as at 13 for accommodating the lock nut 14 and a binding terminal 15. Coöperating with the sparking terminal 12 of the electrode 11 is the ground electrode indicated generally by the numeral 16, this electrode 16 extends from the lower edge of the casing and has a portion 17 bent at right angles to the main portion and arranged in suitable spaced relation with the under surface of the sparking point 12 to provide a spark gap 18, while the outer portion is bent upwardly and inwardly as at 20 to provide another sparking point which is arranged in close relation with one side of the sparking point 12 of the central electrode 11, the space therebetween providing another spark gap 21.

By the provision of this peculiar construction it is to be observed that two sparking gaps 18 and 21 are provided between the two electrodes 11 and 16 and prevents the spark plug from fouling because either one of the gaps will fire should the other become foul to consequently insure of the burning off of any oil or carbon that might lodge between the two gaps. Moreover by

this peculiar construction a magnetic field is built around the firing point or gap that so intensifies the spark as to produce a high frequency spark.

5 In Figs. 3 and 4 there is shown a slightly modified form of the invention. In reducing this feature of the invention to practice, instead of employing the ground electrode 16, another ground electrode indicated
10 generally by the numeral 22 is employed and consists of a body formed from a single piece of wire the intermediate portion of which is bent into a substantially U-shaped configuration and consists of a relatively flat medial portion 23 and relatively and inwardly inclined arms 24 which are joined at an angle with the side portions 25 of the body so as to provide opposed sparking points 26 which are arranged upon opposite sides and in suitable spaced relation with the sparking point 27 of the central electrode 28 carried in the insulator body of a construction similar to the insulator body
15 4. In this connection it is to be noticed that the outer end of the sparking point is suitably spaced to the medial portion 23 to provide another spark gap. Finally the terminals 29 of the body are anchored in opposite points in the lower edge of the
20 casing 30 which is of a construction similar to the casing 1. It will thus be seen that three sparking gaps are provided by the use of this ground electrode 22 in conjunction with the central stationary electrode 28 and owing to the peculiar arrangement of these electrodes the accumulation of carbon
25 thereon, which causes a short circuit or miss firing, is obviated and in addition the magnetic field built up around the firing points
30 or gaps so intensifies the spark as to produce a high frequency spark.

It is thought in view of the foregoing description that a further detailed description of the operation of the invention is entirely unnecessary. Likewise it is believed 45 that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a 50 limited sense. It is also to be understood that the language used in the following claim is intended to cover all the generic and specific features of the invention herein described and all statements of the scope of 55 the invention which as a matter of language might be said to fall therebetween.

What I claimed is:—

In a spark plug, a casing, an insulator body therein, a central electrode carried 65 within the body and projecting beneath the lower edge thereof to provide a sparking point, a ground electrode carried with and depending from the lower edge of the casing and having a portion bent at right angles to the main portion and positioned in suitable spaced relation beneath the sparking point to provide a spark gap, the outer portion of the ground electrode being bent 70 upwardly; and a contact terminal extending 75 from the upper portion and arranged in suitable spaced relation with the side of the first mentioned sparking point to provide another spark gap between the two electrodes.

In testimony whereof I affix my signature.
SAMUEL W. HYATT.
